INKSTAND

Frank M. Ashley, Great Kills, N. Y., assignor to
Lewis Gompers, as trustee, New York, N. Y.

Application September 15, 1936, Serial No. 100,831

8 Claims. (Cl. 120—4)

My invention relates to inkstands.

The object of my invention is to provide an inkstand in which a dip-tube is used and embodying means by which the dip-tube may be supported in a vertical or in an inclined position so that a pen holder carried thereby may be held in a position desired by the user.

A further object is to provide means for holding the dip-tube in its adjusted position by friction 10 while permitting it to be moved when force is applied to overcome the frictional resistance.

A further object is to provide an inkstand in which a pen is supported and in which the pen-holder serves as a closure for the inkwell, and to 15 provide an inkwell which may be practically filled with ink without smudging the pen-holder.

Referring to the drawing which forms a part of this specification:

Fig. 1 is an elevational sectional view thru an 20 inkstand embodying my invention.

Fig. 2 is a similar view to that shown in Fig. 1 showing the dip-tube supported in an inclined position.

Fig. 3 is a plan view showing the cover portion 25 consisting of a two-part ring, the inner wall of which is formed spherical as illustrated in Fig. 7.

Fig. 4 is a vertical sectional view of a lining member formed to fit the end of a pen-holder that the user may wish to use as a closure for 30 the inkwell, and preferably made of soft rubber whereby a tight closure of the well may be insured.

Fig. 5 is a dip-tube carried by the rotary member of the stand.

Fig. 6 is a cross sectional view thru a rotary member having an outer wall formed spherical to fit into the two part socket formed in the ring 35 shown in Fig. 7.

Fig. 7 is a vertical sectional view of a two-part ring formed with a spherical socket and having a circular outer wall.

Fig. 8 is a plan view of a soft rubber ring and may also be made of sponge rubber.

Fig. 9 is a vertical sectional view showing a construction in which the dip-tube is formed directly in the rotatable or tiltable element.

Figure 9 illustrates the most simple form of my invention, the cover portions all being located 50 in the top of the body portion 10 in such a manner as to prevent its lower end to project any considerable distance into the well 11, thus permitting the use of a shallow well which will hold as much ink as a deeper one would hold were the top parts 55 to project into the well a greater distance, as

shown in Figures 1 and 2, without the lower end coming into contact with ink.

The body portion 10 may be made of glass or other suitable material, and is formed with a circular opening in its upper side into which may be fitted the two-part ring 12 directly, if desired, but I prefer to use a soft rubber ring 13 and seat the two-part ring 12 therein after the ball-like portion 14 has been placed therein as illustrated in Figures 1, 2 and 9.

The spherical wall of the element 14 is slightly larger in diameter than that of the socket 15' in which it rests, and the rubber ring 13 acts to embrace the two-part ring 12 and close the socket to effect a close frictional engagement whereby the dip-tube 15 seated therein is held in its adjusted position of rest but may be moved by a lateral pressure which overcomes the said frictional resistance.

The soft lining member of the dip-tube, indicated by 16 may be formed to fit into the conical dip 15 of Figure 9, if desired.

The advantage of the use of the separate dip-tube is that it can be raised or lowered a predetermined distance to accommodate pens of different lengths, and being interchangeable with other dip-tubes made to fit in stiff sliding relation in the ball-like member, will permit any desired shape of pen-holder to be used as a closure for the well.

When a pen-holder is placed in position as illustrated in Figure 1, the dip-tube may be tilted to the desired angle at once without injury to the pen-holder.

By the use of the divided ring construction, the parts may be quickly and easily assembled or separated for cleaning, etc.

Those persons skilled in the art to which this invention pertains will have no difficulty in understanding its construction.

The construction may be modified and changed in a number of ways without departing from the invention disclosed and I therefore do not wish to be limited to the specific forms shown herein, but shall be protected only by the scope of the claims 45 granted.

Having thus described my invention I claim as new:

1. An inkstand formed with a body portion comprising a well, and a dip-tube carried by the 50 body portion in tiltable relation.

2. The construction defined in claim 1, together with; and means comprising frictional surfaces in contact with each other for holding the dip-tube in an adjusted position of rest.

3. An inkstand comprising a body portion, a two-part ring formed with a socket, and a dip-tube construction adapted to be held in position by compression between said two parts of the ring.
4. The construction defined by claim 3, together with, and means encircling said two-part ring to hold it together.
5. An inkstand formed with a body portion having an opening in communication with the well of the stand, an elastic ring held in said opening, a two-part ring held together by said elastic ring, and a tiltable funnel supported by the two-part ring.
6. The construction defined by claim 5, together with; said funnel being held in vertically adjustable relation to said two-part ring.
7. An inkstand formed with a body portion comprising a well, a dip-tube carried by the body portion in tiltable relation, and a soft rubber lining for said dip-tube.
8. An inkstand formed with a body portion comprising a well, a dip-tube carried by the body portion comprising a ball-like outer surface, and a two-part socket in which said ball-like outer surface fits in relatively movable relation.

FRANK M. ASHLEY.
